TRAVERSE CONTROL

Harold E. Balsiger, Waynesboro, Pa., assignor to
Landis Tool Company, Waynesboro, Pa.

Original application April 21, 1937, Serial No.
138,245, now Patent No. 2,249,343, dated July
15, 1941. Divided and this application Novem-
ber 3, 1939, Serial No. 302,761

7 Claims. (Cl. 121—45)

This is a division of Balsiger application Serial No. 138,245, filed April 21, 1937, for Reversing mechanisms, now Patent No. 2,249,343, granted July 15, 1941.

My invention relates to traverse control mechanisms and particularly those which are hydraulically operated.

An object of my invention is to provide a simplified start and stop device for a hydraulic traverse mechanism.

A further object is to provide means for automatically bypassing a traverse speed control valve when pressure on the traverse mechanism is released.

In the drawing, Figure 1 is a front elevation of a metal working machine cut away to show the relation between the various parts.

Referring to the drawing, Figure 1, numeral 10 indicates the bed of a metal working machine, and 11 a work carriage slidably mounted thereon. Said carriage may be actuated manually by any of the well known manual traverse mechanisms. Power means for effecting a reciprocating movement of said work support include two cylinders 170 and 171 in which are mounted pistons 172 and 173 respectively. Piston ends 174 and 175 are connected to carriage 11 by means of brackets 176 and 177 respectively. Reciprocation of said carriage is effected by a reversing mechanism consisting of a lever 102 actuated by movement of the carriage, a pilot valve 45 shifted by said lever for directing fluid under pressure to shift a reversing valve 55. This reversing mechanism is described in detail in my application Serial No. 138,245 of which this is a division.

A lever 37 acts as a start and stop control for the traverse mechanism as well as for a work drive motor, not shown. A cam surface 40 on said lever actuates a work drive motor control switch 41. Said lever is connected by means of link 42 to start and stop valve 43 of the traverse control mechanism. Said mechanism consists of a housing 44 in which is mounted a relief valve 50, a start and stop valve 43, a reversing valve 55, and a bypass valve 58. The bore containing said relief valve extends the entire width of the housing 44, the end of said bore is closed by a cap 51 inserted therein. A passage 53 connects valve 50 with start and stop valve 43. A passage 54 connects valve 43 with reversing valve 55. An extension 57 of passage 54 serves to direct fluid to the left end of bypass valve 58. A spring 65 mounted in a hollow end portion of said valve 58 urges said valve to the left. Two ports 59

and 60 are connected by passages thru the front part of the housing 44 in which are mounted a pair of check valves 61 and 62. Said ports are also connected to the opposite sides of a throttle valve 71. Each of said check valves is inserted in a recess 59' and 60' which in turn is connected to port 59 or 60 as shown. Both of said check valves are supplied with fluid under pressure thru passage 54a. Adjusting screws 90 and 91 determine the maximum opening of said check valves. An exhaust passage 63 connects the right hand end of all the valves. A spring 65 serves to hold the bypass valve 58 in an extreme left hand position in the absence of fluid under pressure at that point. Reversing valve 55 directs fluid from the passage 54 alternately through passages 160 and 161 to opposite ends of a traverse motor.

The start and stop valve 43 and lever 37 are shown in central position. In the left hand position of said lever the switch 41 is open rendering the headstock motor inoperative. When said lever is in the left hand position, valve 43 is in the extreme right hand position and thus cuts off the supply of fluid under pressure from passage 53. Passage 54 is connected to exhaust passage 63. In the central position of lever 37 switch 41 is closed and the headstock motor is started. In the right hand position of lever 37 the switch is still held in closed position and valve 43 is moved far enough to the left to open passage 53 completely and to close passage 63. Fluid under pressure is then directed through passages 54 and 54a to the traverse motor.

The relief valve 50 consists of a movable piston element having a hollow portion in which is mounted a spring 75. Said spring urges said piston to the left or closed position against a seat formed by the inner end of cap 51. The other end of said spring is seated in a cup shaped member 76 having a hole 77 therein to prevent fluid from becoming locked between said cup and the end cap 78. Other holes (not shown) in the periphery of said member 76 permit passage therethru of fluid in exhaust passage 63. An adjusting screw 79 is threaded in said cap and bears against said cup 76 for varying the setting of the valve. In response to an excess of fluid, relief valve 50 will be shifted enough to permit such excess to enter port 80 from passage 81 in said valve. From port 80 fluid may pass through passage 82 to exhaust passage 63. A valve 97 in the exhaust passage 63 is held against its seat by means of a spring 99. The purpose of this valve 55 is to keep a slight back pressure in the exhaust

system and at the same time to prevent drainage of fluid from the control valve.

Operation

To start the machine the operator must open throttle valve 71 to permit fluid to pass therethru between the cylinders 170 and 171, then he must shift valve 43 to the left by means of lever 37. Cam 40 on the lower end of said lever actuates limit switch 41 to start a work drive motor, not shown.

Fluid under pressure is supplied to the valve housing 44 from pump 180 through line 181 from which it passes through relief valve 50 and passage 53 to valve 43. Upon shifting valve 43 to the left fluid from passage 53 is directed to passage 54 through which it passes to passage 57 and then to the left end of bypass valve 58 shifting said valve to the right thus preventing passage of fluid therethru between cylinders 170 and 171 and causing fluid to pass through throttle valve 71. Said valve 71 determines the traverse speed of the carriage 11. Fluid under pressure passes from passage 54 through passage 54a and then through either or both of the check valves 61 and 62 and ports 59 and 60 to insure that the rod ends of the two cylinders 170 and 171 and a connecting line are kept full of oil and free of air. When pump 180 is stopped, check valves 61 and 62 prevent fluid from draining out of the cylinders. When lever 37 and valve 43 are shifted to stop position the passage 53 is connected to exhaust line 63 and the fluid is returned to the reservoir. Pressure is thus removed from the left end of valve 58 and said valve is shifted to the left by spring 65. In this position of valve 58 lines 72 and 73 leading to the inner ends of cylinders 170 and 171 respectively, bypass throttle valve 71 and thus permit a free flow of fluid from one cylinder to the other while the carriage 11 is traversed manually.

I claim:

1. A grinding machine having a reciprocable carriage, a hydraulic motor for driving said carriage comprising a pair of cylinders, a start and stop valve, a piston in each cylinder, connections between said motor and said carriage, a control valve for directing fluid under pressure alternately to one end of each of said cylinders, a line connecting the opposite ends of said cylinders, a throttle valve in said line for controlling the speed of said carriage, a fluid operated bypass valve for permitting an unobstructed passage of fluid around said throttle valve, and means for opening said bypass valve when the supply of fluid to said traverse motor is cut off by said start and stop valve.

2. A grinding machine having a reciprocable carriage, a hydraulic motor for driving said carriage comprising a pair of cylinders, a start and stop valve, a piston in each cylinder, connections between said motor and said carriage, a control valve for directing fluid under pressure alternately to one end of each of said cylinders, a line connecting the opposite ends of said cylinders, a throttle valve in said line for controlling the speed of said carriage, a fluid operated bypass valve for permitting an unobstructed passage of

fluid around said throttle valve, means for opening said bypass valve when the supply of fluid to said traverse motor is cut off, and means for directing fluid under pressure to operate said bypass valve when fluid is also directed to said motor by said start and stop valve.

3. In a grinding machine, a bed, a carriage slidably mounted thereon, means for causing a reciprocating movement of said carriage comprising a hydraulic motor, a reversing valve for said motor, a line connecting opposite sides of said motor, a throttle valve in said line for controlling the speed thereof, a valve for bypassing fluid around said throttle valve, a start and stop valve for controlling the flow of fluid to said reversing valve, and means for operating said bypass valve in response to fluid under pressure from said start and stop valve.

4. In a grinding machine, a movable carriage, manual means for effecting a traversing movement of said carriage, power means for effecting a traversing movement of said carriage comprising a fluid motor, a supply of fluid under pressure, a start and stop valve for controlling said supply, a passage connecting opposite sides of said motor, a throttle valve in said passage for controlling the speed of said motor, a pressure operated valve for bypassing said throttle valve, and pressure responsive means for actuating same, connections from said start and stop valve to said motor and said pressure responsive means for closing said bypass valve during power traverse to cause fluid to pass thru said throttle valve.

5. In a grinding machine, a movable carriage, manual means for effecting a traversing movement of said carriage, power means for effecting a traversing movement of said carriage comprising a fluid motor, a supply of fluid under pressure, a start and stop valve for controlling said supply, a valve for adjusting the rate of movement of said carriage, a pressure operated bypass valve, fluid connections from said start and stop valve to said motor and said bypass valve for actuating said bypass valve to connect opposite sides of said motor and for rendering said rate adjusting valve inoperative when the supply of fluid to said motor is cut off.

6. In a metal working machine, a movable member, a hydraulic system including a motor for effecting movement of said member, a valve for controlling the rate of movement of said motor at any point in its travel, a start and stop valve and a pressure operated bypass valve for rendering said rate control valve operative or inoperative in response to starting or stopping the flow of fluid under pressure from said start and stop valve.

7. In a metal working machine, a movable member, a hydraulic system including a motor for effecting movement of said member, a valve for controlling the rate of movement of said motor, a start and stop valve and a pressure operated bypass valve for rendering said rate control valve operative or inoperative at any point in the travel of said motor in response to starting or stopping the flow of liquid under pressure from said start and stop valve.

HAROLD E. BALSIGER.
